SAFETY RAZOR

Mayner D. Brock, Kansas City, Mo.

Application September 28, 1936, Serial No. 102,914

6 Claims. (Cl. 30—51)

This invention relates to improvements in safety razors.

The principal object of the present invention is the provision of a safety razor having novel means whereby the blade is secured in the operative position in the blade holder.

Another object is the provision of a convenient means whereby the blade is released from the secured operative position.

10 A further object of the present invention is the provision of blade and blade holder having guard teeth so constructed that the blade when reversed end for end in the holder presents those portions of the cutting edge which had been in alignment with the guard teeth to positions intermediate the guard teeth.

Another object of the invention is the provision of a safety razor wherein a planar blade is so positioned in the holder as to be readily accessible for cleaning without removal from the holder.

Other objects are economy and simplicity of construction, ease and convenience of operation, and adjustability of the parts to insure the use of the entire cutting edge of the blade.

25 With these and other objects which will appear during the course of the specification, in view, reference will now be had to the drawing, wherein—

Figure 1 is a front elevation of a safety razor embodying this invention.

Fig. 2 is a side elevation of the razor shown in Figure 1.

Fig. 3 is an enlarged fragmentary plan view of the blade holder with the blade secured in the operative position.

Fig. 4 is an end elevation of the parts shown in Fig. 3.

Fig. 5 is a sectional view taken on line V—V of Fig. 3.

40 Fig. 6 is a fragmentary sectional view taken on line VI—VI of Fig. 5.

Fig. 7 is a plan view of the blade detached.

The blade holder 10 preferably made of a single piece of sheet metal, comprises a U-shaped head 12 and a handle 14 extending outwardly from the front wall thereof. Without deviating from the invention, the handle might be made of a different material and conveniently attached to the head member. The U-shaped head member comprises two resilient end walls 16 which are interconnected by a front wall 18. The end walls 16 are normally in substantially parallel relation and each is provided with an outwardly extending ledge 20 adapted to form an off-set wall 22 against which the blade is adapted to rest

as hereinafter set forth and shown. This wall 22 may be under-cut as clearly shown in Fig. 4 to preclude upward movement of the blade.

The free ends of walls 16 are adapted to receive a spreader bar 24 therebetween by means of 5 which the end wall may be spread apart. The end portions of the spreader bar are recessed to form tongues 26 and 28 which span the neck 30 of the outwardly disposed projection 32 at the free extremity of each end wall respectively. 10 These projections 32 are off-set outwardly to form inclined walls 34 over which the end surface of spreader bar 24 rides as it is oscillated about its minor axis to force the end walls apart for reasons hereinafter set forth. The tongue 26 rests 15 in the notch 36 while the tongue 28 may, by sufficient force, be caused to move along the arcuate edge 38 until it meets the stop 39.

Carried by each of the end walls 16 intermediate projection 32 and wall 22 is an inwardly projecting lug 40 adapted to over-lay the end portions of the blade, as shown, to prevent it from moving away from the blade holder.

As clearly shown in Fig. 7, and in other views, blade 44 is preferably made of a substantially 25 rectangular piece of resilient sheet metal having similar notches 46 formed in each corner thereof to form end tongues 48. Blade 44 may have a single cutting edge 50 along one of its longitudinal edges or it may have a cutting edge at each of its 30 longitudinal edges as shown in the drawing. When the two cutting edges are provided as shown, the spreader bar 24 serves to protect the back edge when the blade is in the operative position. When a single edge blade is used it is apparent that the spreader bar might be omitted and the blade holder made simpler. However, in such a structure it would be necessary to either flex the blade into position or remove the blade from the holder, or the end walls might be forced 35 apart manually without the use of spreader bar 24.

The front wall 18 of the blade holder is provided at its upper edge with a series of equally spaced apart guard teeth 52. The guard teeth 45 are so positioned relative to the cutting edge of the blade and the end wall that when the blade is reversed end for end in the holder those portions of the cutting edge formerly in alignment with the guard teeth will be positioned intermediate said teeth. By so arranging the guard teeth it is evident that a greater portion of the effective cutting edge of the blade may be positioned intermediate the guard teeth to facilitate proper use of all portions of the blade.

Positioned centrally of the cutting edges of the blade is a notch 54 which is adapted to be engaged by a tongue 56 carried by the front wall 18 of the holder. The tongue 56 is off-set at its 5 under surface to form a stop 58 to receive the inner wall of notch 54 for limiting the forward movement of the blade, also the outer free end of tongue 56 overlaps the blade 44 to prevent its movement upwardly from the holder. With the 10 tongue and notch positioned centrally of the blade and blade holder as shown, the blade may be reversed end for end in the frame and the tongue will always engage the notch. In the case of a double cutting edge a notch 54 is provided at each 15 edge of the blade and these notches are in alignment so as to properly register with the tongue regardless of which cutting edge is being used.

To insert the blade in the holder the outer edge of spreader bar is moved downwardly, thereby 20 forcing the end walls a sufficient distance apart to permit the blade to be positioned with the tongues resting on the end walls 16 between wall 22 and lug 40. By raising up on the outer edge of bar 24 the resilient end members will resume 25 their normal position and the lugs 40 will be positioned to overhang the end portions of the blade to secure it in the operative position. The tongue 56 will also overlap the blade to preclude any 30 outward movement of the blade during the shaving operation.

The blade 44 may be flexible or substantially rigid, however, it has been found best to make the blade of a thin resilient material which may be flexed to facilitate to a certain degree the position 35 of the blade in the holder and its removal therefrom.

Referring to Fig. 5, it will be observed that the end walls together with the blade and front wall form an inverted receptacle for the reception 40 of the soap as it passes through the slot formed between the blade and the guard teeth. The shaving material so deposited during the shaving operation may be easily removed and the razor blade cleaned without removing the blade from the holder. No obstructions are encountered on 45 the underside of the blade between the cutting edges. The spreader bar 24 in certain instances, and especially when a blade with a single cutting edge is used, might be eliminated.

Having thus described the invention, what is 50 claimed as new and desired to be secured by Letters Patent is:

1. A razor comprising a blade holder having 55 resilient end walls connected together by a front wall and terminating adjacent the rear edge of the blade carried thereby; an overhanging lug adjacent the free end of each of said end walls adapted to normally secure a cutting blade in said holder; and means adapted to engage the

free ends of said end walls operable to relatively move said end walls to disengage said lugs from said blade.

2. A razor comprising a blade; a blade holder having resilient end walls connected together by 5 a front wall; a handle carried by said front wall; an inwardly projecting lug carried by each of said end walls adapted to override end portions respectively of each blade to secure the blade in the operative position; and a bar interposed between the free ends respectively of said end walls to the rear of said blade operable to force apart 10 said end walls.

3. A razor comprising a blade; a blade holder having means for securing the blade in the operative position; a series of equally spaced guard teeth formed in the front wall of said blade holder, said teeth being so positioned relative to the cutting edge of the blade whereby when the blade is reversed in the holder those portions of the cutting edge formerly in alignment with the teeth 15 will be positioned intermediate said teeth.

4. A razor comprising a blade; a blade holder having a front wall and means for securing the blade in a predetermined operative position; a 20 series of equally spaced-apart guard teeth formed in said front wall adjacent the cutting edge of said blade, the opposite end teeth of said series being positioned at different distances from their 25 respective adjacent blade ends whereby when the blade is inverted that portion of the blade formerly in alignment with the teeth will be in alignment with the spaces intermediate the teeth.

5. A razor comprising a blade; a blade holder having resilient end walls connected together by 30 a front wall and terminating respectively at points to the rear of the blade carried by said holder, a lug adjacent the forward portion of each of said end walls adapted to limit the forward movement of said blade; an inwardly projecting lug 35 carried by each of said end walls adapted to engage opposite ends respectively of said blade to secure it in the operative position; and a spreader bar positioned between said end walls operable to force said end walls apart to release said lugs 40 from said blade.

6. A razor comprising a blade; a blade holder having spaced-apart, substantially parallel resilient end walls connected together by a front 45 wall, a lug adjacent the forward portion of each of said end walls adapted to limit the forward movement of said blade; an inwardly projecting lug carried by each of said end walls adapted to engage opposite ends respectively of said blade to secure it in the operative position; and a spreader bar, positioned between said end walls, at the rear 50 of and in substantially planar alignment with said blade, operable to force said walls apart.

MAYNOR D. BROCK.
